UNITED STATES PATENT OFFICE.

EARL C. BUNNELL, OF STRATFORD, CONNECTICUT.

GOLF-TEE PACKET AND GOLF TEE.

Application filed April 13, 1926. Serial No. 101,769.

This invention relates to a golf tee packet and to a golf tee.

An object of the invention is to provide an article to be employed by golfers to "tee" a golf ball in place of a built-up clay mound as now commonly utilized.

A further object is to provide a packet in which a number of the novel tees are placed to be removed by a golfer, one by one, as the tees may be required.

A further object is to provide a tee for golfers which will consist of a suitable blank or piece of material adapted to be formed to a shape suitable for supporting a golf ball above the ground in position to be conveniently struck and driven.

A further object is to provide a packet for golf tees, which packet will consist of separate, flat sheets of suitable material, such as paper, cardboard, parchment, celluloid, or the like, conveniently joined to each other to constitute said packet, each sheet of the packet having outlined therein a readily removable blank to be formed to a shape adapted to rest upon the ground and nicely support a golf ball in position to be struck and driven.

A further object is to provide a tee which will consist of a flat blank or disc of suitable material, such as paper, cardboard, parchment, celluloid, or the like, bounded at its outer margin by a relatively large circumference, at its inner margin by a relatively small circumference, and at its ends, which are adjacent each other, by interlocking elements adapted to the purpose of securing said ends together to provide a hollow frusto-conical body the large, open end of which is adapted to rest upon the ground, and the small, open end of which is adapted to provide a seat for a golf ball which is to be struck and driven.

A further object is to provide interlocking elements of unique and improved structure.

And a still further object is to provide a packet for the tees consisting of a plurality of flat sheets of material each having a readily removable tee, wherein all of the sheets of the packet will be in superimposed relation to each other to have a tendency toward keeping each sheet flat, and wherein each blank to form a tee will be situated within the margins of each sheet so that the

margins of a sheet will have a tendency toward keeping each blank flat until ready for use.

With the above objects in view, as well as others which will appear as the specification proceeds, the invention comprises the construction, arrangement, and combination of parts as now to be fully described and as hereafter to be specifically claimed, it being understood that the disclosure herein is merely illustrative and meant in no way in a limiting sense, changes in details of construction and arrangement of parts being permissible so long as within the spirit of the invention and the scope of the appended claims.

In the accompanying drawing forming a part of this specification,

Fig. 1 is a plan view of a blank or disc for constructing the improved tee;

Fig. 2 is an edge view of the blank or disc of Fig. 1;

Fig. 3 is a plan view of the tee formed to shape and ready for use;

Fig. 4 is an elevational view of the tee as when in use, a golf ball resting upon the tee;

Fig. 5 is a perspective view of superimposed blanks or discs having the features of the blank or disc disclosed in Fig. 1 and suitably and detachably joined together to provide a packet;

Fig. 6 is a perspective view of a packet consisting of suitably joined sheets each having a blank or disc removable therefrom and constructed as disclosed in Fig. 1; and

Fig. 7 is a perspective view of a modified form of tee.

With respect to the drawing, 10 denotes a preferably flat blank or disc of material, such, for example, as paper, cardboard, parchment, celluloid, or the like, which is bounded at its outer margin by a relatively large circumference 11, at its inner margin by a relatively small circumference 12, and at its ends by elements, denoted 13 and 14, respectively, which are adjacent each other and are adapted to be interlocked to secure the ends of the blank together.

The blank 10 is of that construction to provide a hollow frusto-conical body when said elements 13 and 14 are made to interlock, the circumference 11 defining the large, open end of said frusto-conical body adapt-

ed to rest upon the ground, and the circumference 12 defining the small, open end of said frustro-conical body adapted to provide a seat for a golf ball A, said golf ball 5 being adapted to fit said seat in about the manner as disclosed in Fig. 4. The golf ball when so supported is in stable position ready to be conveniently struck and driven by a golf club.

10 The interlocking elements 13 and 14 may each or either contain an adhesive, as in Fig. 7, or be constructed in some manner different from those shown. I prefer, however, to utilize interlocking elements of the structure illustrated in Figs. 1 to 6.

15 Of the element 13, numeral 15 denotes a hook member providing an upwardly opening slot 16 at the end 17 of the blank 10 and adjacent the lower or ground engaging end 20 of the tee. Of the element 14, numeral 18 denotes a hook member providing a downwardly opening slot 19 at the end 20 of the blank 10 and at the lower or ground engaging end of the tee. The hook members 15 25 and 18 are complementary and are adapted to interlock, slots 16 and 19 then interengaging as more clearly disclosed in Figs. 3 and 4 to resist tensions tending to spread the lower portions of the ends 17 and 20 apart.

30 When said hook members 15 and 18 are interlocked they are preferably both at the inner side of the tee. Numeral 21 represents a shoulder upon the end 17 of the blank 10 and adapted to be positioned at the inner face of the upper portion of the end 20 of the blank 10, so that the hook member 18, said upper portion of the end 20, and said shoulder 21 can cooperate to resist compressions tending to cause the upper portions of the ends 17 and 20 to overlap. That is to say, 35 the elements 13 and 14 together provide a tension lock adjacent the lower or ground engaging end of the tee, and a compression lock adjacent the upper, or golf ball receiving end of the tee, both adapted to cooperate, to insure the frusto-conical shape of the tee. Obviously, the tendency toward overlapping of the upper portions of the ends of the tee caused by the weight of the golf ball is effectually prevented by the compression lock, 40 while the tendency toward spreading apart of the lower portions of the ends of the tee caused by said weight is effectually prevented by said tension lock. The compression lock cooperates with the tension lock in insuring the set positions of the hook members, while the tension lock likewise cooperates with the compression lock in insuring the set position of the shoulder 21 relatively to the upper portion of the end 20 of the blank 10. In other words, the compression and tension locks coact in the performance of their intended functions.

45 In Fig. 5 I have disclosed superimposed flat blanks or discs 10 detachably joined to-

gether to provide a packet 22. The superimposed blanks or discs have a tendency toward keeping each blank or disc flat.

In Fig. 6 I have illustrated superimposed flat sheets 23 detachably joined together as at 24 to provide a packet 25, each sheet 23 having a blank or disc 10 situated within the margins of the sheet, 26 representing perforations in each sheet defining the outline of each blank or disc and rendering the blank or disc readily removable from the sheet. The superimposed sheets have a tendency toward keeping each sheet flat, and the marginal portions of each sheet have a tendency toward keeping each blank flat until ready for use.

What I claim is:

1. As an article of manufacture, a golf tee consisting of a shaped blank of material providing a hollow frustro-conical body including a relatively large, open, lower end adapted to rest upon the ground and a relatively small, open, upper end adapted to provide a seat for a golf ball, and means securing the ends of the blank to each other, 90 said means including a tension lock adjacent the lower end of said tee and a compression lock adjacent the upper end of said tee, for the purpose described.

2. As an article of manufacture, a golf tee blank including an outer circumferential margin, an inner circumferential margin, spaced apart ends which are adjacent each other, and means adapted to secure said ends to each other to provide a hollow frustro-conical body including a large end adapted to rest upon the ground and a small end providing a seat adapted to support a golf ball, said means including a tension lock adjacent said large end adapted to resist forces 105 tending to move the lower portions of the blank ends apart, and a compression lock adjacent said small end adapted to resist forces tending to move the upper portions of the blank ends to overlapping relation, said 110 tension and compression locks thus cooperating to make said tee stable when supporting a golf ball.

3. As an article of manufacture, a golf tee blank including an outer circumferential 115 margin, an inner circumferential margin, spaced apart ends which are adjacent each other, and means adapted to removably secure said ends to each other to provide a hollow frustro-conical body including a 120 large end adapted to rest upon the ground and a small end providing a seat adapted to support a golf ball, said means comprising a hook member providing an upwardly opening slot at one end of the blank and 125 adjacent the lower end of the tee, a hook member providing a downwardly opening slot at the other end of the blank and at the lower end of the tee, and a shoulder upon an end of the blank and adapted to be positioned 130

at the inner face of the upper portion of the opposite end of said blank, said hook members, shoulder and upper portion being adapted to interengage each other in such manner as to provide a tension lock adjacent said large end of the tee to resist forces tending to move the lower portions of the blank ends apart, and a compression lock adjacent said small end of the tee adapted to resist forces tending to move the upper portions of the blank ends to overlapping relation.

Signed at Bridgeport, in the county of Fairfield, and State of Connecticut, this 12 day of April, A. D. 1926.

EARL C. BUNNELL.
